UNITED STATES PATENT OFFICE.

JOSEPH F. BIGGS, OF RICHMOND, VIRGINIA.

DESIGN FOR A TALKING-MACHINE CABINET.

57,306.

Specification for Design.

Patented Mar. 15, 1921.

Application filed August 12, 1920. Serial No. 403,178. Term of patent 14 years.

To all whom it may concern:

Be it known that JOSEPH F. BIGGS, a citizen of the United States, residing at the city of Richmond and State of Virginia, has invented a new, original, and ornamental Design for a Talking-Machine Cabinet, of which the following is a specification, reference being had to the accompanying drawing, forming part thereof.

Figure 1 is a perspective view of the talking machine cabinet or case showing the new design.

Fig. 2 is a perspective view of the cabinet viewing the same from the opposite end, and showing the sectional doors partly ajar also disclosing the design.

What is claimed is:

The ornamental design for a talking machine cabinet, as shown.

JOSEPH F. BIGGS.
